UNITED STATES PATENT OFFICE.

EDWARD P. KING, OF PAINESVILLE, OHIO.

SLEEPING-GARMENT.

1,143,282.

Specification of Letters Patent. Patented June 15, 1915.

Application filed May 3, 1913. Serial No. 765,217.

To all whom it may concern:

Be it known that I, EDWARD P. KING, a citizen of the United States, residing at Painesville, in the county of Lake and State 5 of Ohio, have invented a certain new and useful Improvement in Sleeping-Garments, of which the following is a full, clear, and exact description, reference being had to the accompanying drawings.

10 One of the objects of the invention is to provide means in the sleeves and legs of sleeping garments, such as pajamas, to prevent them slipping up over the elbows and knees, and thus overcome the very objectionable feature of the ordinary pajama.

Another object is to provide means for attaching the trousers to the coat of the sleeping garment so that the uncomfortable pressure of the usual cord around the top of the 20 trousers may be done away with, making the garment more comfortable to sleep in.

To accomplish these objects, I provide elastic knit cuffs of washable material for the wrist and ankles and funnel-shaped 25 pieces of washable fabric attached to these cuffs and to the inside of the sleeves and trouser legs. The elastic cuffs fit around the wrists and ankles and prevent the sleeves and legs of the garment from slipping up 30 over the elbows and knees. As a means for attaching the trousers to the coat to give a union suit effect, and do away with the uncomfortable pressure of the cord around the top of the trousers, I sew a belt around the 35 inside of the coat, having buttons onto which the top of the trousers are buttoned.

40 My invention is illustrated in the accompanying drawing and is hereinafter more fully described and the essential characteristics set forth in the claims.

In the drawings, Figure 1 is an elevation of an improved pajama having a portion of one sleeve and one leg broken away, and one side of the coat turned back to show the 45 belt to which the trousers are attached; Fig. 2, is a detail of one of the bell-shaped cuffs showing the relative position of the foot and ankle in broken lines; Fig. 3 is a sectional detail of a portion of the coat showing the 50 arrangement of the belt with the trousers buttoned to it; and Fig. 4, is a view of a portion of the trousers leg showing another method of attaching the elastic cuff.

In the drawings, 5 indicates the coat of 55 the pajama, 6 indicates the trousers, and 7 and 8 indicate respectively the bell-shaped

fabric sewed on the inside of the sleeves and legs respectively.

9 and 10 indicate respectively the cuff of elastic fabric for the wrist and ankle.

I make cuffs 9 and 10 of washable elastic knit fabric so that they may be permanently sewed to the legs and sleeves of the garment and be washed with the garment without being injured in any way. At the upper edge 60 of these elastic cuffs, that is the edge nearer the elbows and knees, I sew a funnel-shaped piece of washable fabric of somewhat less elastic material. These pieces have been heretofore designated 7 and 8, and, as 65 shown, are sewed to the sleeves and legs of the garment, as at 12 in Fig. 2. Thus they are substantially the full size of the leg or sleeve at their upper edges and serve to guide the elastic cuff over the hand or foot. This 70 method of attaching these elastic cuffs to the sleeves and legs does not impair the suit-like appearance of pajamas, which is a desirable feature of all well-made garments of this nature.

The belt, which is sewed inside of the coat and to which the trousers are buttoned, is designated 15. This belt 15 extends substantially around the inside of the coat and is sewed thereto at its upper edge 16. On 80 the outside of the belt, that is, between the belt and the coat, are sewed a suitable number of buttons 18 which are engaged by corresponding button holes in the top of the trousers. The top of the trousers are turned 85 over the cord 20, as shown in Fig. 3, just above the buttons 18. However, this cord 20 may be entirely done away with when the belt 15 is used, if so desired. The use of this belt makes it very convenient to adjust the length of the trousers by merely 90 changing the position of the buttons on the belt; or by having more than one set of buttons on the belt, one set being above the other, it would only be necessary to unbutton the trousers from one set of buttons and 95 button them onto the other set to change the length of the trousers. This method of supporting the trousers practically makes a 100 union suit of the pajama and prevents the 105 trousers slipping around the body while in bed.

In cases where the appearance of the garment is not such an important feature, as in pajamas used by firemen, for example, 110 where it is necessary to draw on outer garments very quickly, I attach the funnel-

shaped fabric 8 to the outside of the sleeve and leg, as shown in Fig. 4. It is obvious that outer clothes might be drawn quickly over the cuff when so attached without the under-garment rolling up and becoming bunched and otherwise interfering with putting on the outer garment quickly.

It will be seen from the above description that I have provided a sleeping garment which is more comfortable, in that no cord, embracing the body of the wearer, is needed for the trousers, and the sleeves and legs of the garment are held down and can not roll up and cause uncomfortable bunches about the limbs. I have also accomplished these results without changing the desirable suit-like appearance of the garment.

Having thus described my invention, what I claim is:

- 20 1. In a sleeping garment comprising a coat and trousers, the combination of a belt member extending around the inside of the coat and having its upper edge sewed to the coat, buttons for securing the belt to the trousers, elastic cuffs adapted to embrace the lower portions of the lower limbs of the

wearer, and funnel-shaped knit fabric members secured to the upper portion of said cuffs and to the inside of the lower portion of the trouser legs, whereby any downward strains on said cuffs and trouser legs due to movements of the wearer, will be received by the shoulders.

2. In a sleeping garment comprising a coat and trousers, the combination of a belt 35 sewed to the inside of the coat at its upper edge and with its lower edge depending, buttons on the outside of said belt, located above the lower edge of the coat, on which the trousers may be supported and whereby 40 they may be vertically adjusted, elastic cuffs adapted to embrace the lower portions of the lower limbs of the wearer, and funnel-shaped knit fabric members secured to the upper ends of said cuffs and to the inside of 45 the lower portions of the trouser legs.

In testimony whereof, I hereunto affix my signature in the presence of two witnesses.

EDWARD P. KING.
